DAMPER

Frantz J. Kurth, New York, N. Y., assignor to An-
emostat Corporation of America, New York,
N. Y., a corporation of Delaware

Application December 8, 1942, Serial No. 468,278

18 Claims. (Cl. 98—40)

1

This invention relates to dampers, particularly intended for use in association with air diffusing devices through which fresh or treated air is delivered from air supply ducts into rooms or other enclosures for heating, cooling, ventilating or other purposes, and has for its general object to provide a simple, practical damper for regulating not only the total volume of air delivered through a duct to an outlet or diffusing device, but also the proportionate amount of the total volume delivered to different portions of the outlet or diffusing device, thereby to insure the flow of either substantially equal amounts or different amounts of air through different portions of the outlet or diffusing device according to requirements in particular instances.

With the foregoing and other objects in view, which will become more fully apparent as the nature of the invention is better understood, the same consists in a damper embodying the novel features of construction, combination and arrangement of parts as will be hereinafter more fully described, illustrated in the accompanying drawings and defined in the appended claims.

In the accompanying drawings, wherein like characters of reference denote corresponding parts in the different views:

Figure 1 is a central, vertical section through a damper constructed in accordance with one practical embodiment of the invention.

Figure 2 is a horizontal section on the line 2—2 of Fig. 1.

Figure 3 is a fragmentary enlarged vertical section showing in detail the means connecting together certain of the vanes of the damper for simultaneous actuation and illustrating by full and dotted lines open and closed positions, respectively, of the vanes.

Figures 4, 5 and 6 are elevations of different vanes of the damper; and

Figure 7 is a view similar to Fig. 3 illustrating an alternative form of means for simultaneously adjusting certain of the vanes of the damper.

Referring to the drawings in detail, it will be observed that the present damper comprises primarily a frame, designated generally as A, having, in the particular instance illustrated, the general shape of a Greek cross, and that said frame comprises four arms of equal length spaced ninety degrees apart and each composed of a pair of side rails designated as 10, 10. This frame A may be formed from a single length of strap metal of suitable thickness and width bent into the shape described, or it may be formed from any other suitable material in any other suitable

manner and may have any other desired shape. For example, said frame may be cast and instead of having four arms and being in the shape of a Greek cross, it may have any other desired number of arms of the same or different lengths and may be of a shape dictated by the number of arms which it comprises. In any event, arm connecting portions 11 of said frame preferably are spaced equal distances from the center of said frame to adapt said frame to fit either into a cylindrical air supply duct or, equivalently, into the cylindrical neck of an air outlet or diffusing device crosswise or at right angles thereto and to be held therein against lateral shifting movement by the cooperation of said portions 11 with the duct or neck, as the damper particularly is intended for use in association with air outlet or diffusing devices of circular shape and usually such devices have cylindrical necks or are connected to cylindrical ducts through which air is supplied to them and in which the damper is to be located. In this connection, the frame A has been illustrated in the present instance as being disposed in the cylindrical neck 12 of an air outlet or diffusing device B of a well known type comprising a plurality of successively smaller, open-ended, hollow, frusto-conical members 13 spaced successively inwardly of one another to define therebetween a plurality of flaring passageways through the supplied air flows, and as being secured in said neck by means of screws 14 extending through the portions 11 and into said neck. However, the frame A need not include the portions 11 and may be secured in a neck such as the neck 12 or, equivalently, an air supply duct, in any other appropriate manner.

In and extending transversely of each of the arms of the frame A is a series of horizontally disposed, parallel, spaced apart vanes 15 which may 40 be formed from sheet metal or other suitable material and which, in accordance with the invention, are suitably pivoted at their ends to the rails 10, 10 for rotatable adjustment between vertical positions and positions inclined to the vertical as shown by full and dotted lines, respectively, in Fig. 1, either for the purpose in the first instance of permitting supplied air to flow directly downwardly through the spaces between them to the device B or for the purpose in the second instance of deflecting the supplied air either outwardly or inwardly as may be desired. To provide for pivotally mounting said vanes upon the rails 10, 10 said vanes may be provided at their ends with ears 16 bent at right angles thereto, and rivets or other suitable fasteners 17

may extend through aligned holes in said ears and the rails 10, 10, while in order to provide for retaining said vanes in any positions to which they may be rotatably adjusted said fasteners 17 may be employed to clamp said ears against the rails 10, 10 with sufficient tightness so that the resulting friction accomplishes the desired purpose. Each vane 15 of each series of such vanes may, of course, be manually rotated to any desired position independently of each other such vane.

In the embodiment of the invention illustrated in the drawings there are four series of the vanes 15 disposed one to each of the four sides of a central, rectangular space in the frame A, and in accordance with the invention flow of supplied air through said central, rectangular space to the air outlet or diffusing device B is controlled by a fifth series of horizontally disposed, parallel, spaced apart vanes 18 which may be disposed either in the same horizontal plane as the series of vanes 15 or in a horizontal plane below or above the plane of said series of vanes 15. In this connection it will be noted that in the illustrated embodiment of the invention the frame A has secured thereto at the junction of each two adjacent right angularly disposed rails 10, 10 of adjacent arms thereof or, in other words, at each of the four corners of the central, rectangular space in said frame, a vertically disposed angle-iron member 19; that these angle-iron members depend from said frame A; that opposite pairs of said angle-iron members are connected together adjacent to their lower ends by rails 20, and that the vanes 18 extend between said rails 20 and are pivoted thereto, as indicated at 21, in the same manner as the vanes 15 are pivoted to the rails 10, 10, for rotatable adjustment between vertical positions and positions inclined to the vertical for the same purpose as adjustment of the vanes 15. Accordingly, the series of vanes 18 is effective to regulate flow of supplied air through the central, rectangular space in the frame A to the central portion of the outlet device B in the same manner as each of the four series of vanes 15 is effective to regulate flow of supplied air to the related underlying portion of said outlet device. In fact, all of the vanes 15 and 18 are rotatably adjustable not only between vertical positions and positions inclined to the vertical, but to horizontal or substantially horizontal positions to completely or substantially completely cut off flow of supplied air to any part of the outlet device B in case that should be desired in any particular instance. Moreover, the angle-iron members 19 are provided with vertically spaced holes 22 for the selective reception of the screws, bolts or other fasteners 23 by means of which said angle-iron members are secured to the rails 10, whereby said angle-iron members and, consequently, the series of vanes 18 may be vertically adjusted relative to the frame A and, consequently, with respect to the series of vanes 15.

To provide for a greater range of control of the supplied air than is afforded by the series of vanes 15 and 18, four additional series of vanes 24 may be provided, one such additional series between each adjacent two of the angle-iron members 19 or, in other words, one such additional series at each of the four sides of the rectangular space defined by the angle-iron members 19. The vanes 24 of these four additional series may be pivotally connected, as indicated at 25, to the angle-iron members 19 in the same manner as the vanes 15 and 18 are pivotally connected to the

rails 10 and 20, respectively, for rotatable adjustment to regulate flow of supplied air through the sides of said rectangular space, and to this end the vanes 24 of each such series of vanes are, of course, disposed horizontally but in a common vertical plane and are parallel and spaced apart vertically rather than horizontally as in the case of the vanes 15 and 18.

Preferably the vanes 18 are connected together for simultaneous adjustment either manually or automatically by suitable power means which may be thermally or otherwise controlled as, for example, by the temperature of either the supplied air or of the room or enclosure air. Preferably, too, the vanes 18 are divided into two sets disposed respectively to opposite sides of the center of the damper and the two sets of vanes are connected together for reverse operation with respect to each other to insure the same type of air flow regulation at each side of the center of the damper. The vanes of each of the two sets may be connected together in any suitable manner as, for example, by means of tongues 26 bent from the vanes at right angles thereto and pivotally connected, as indicated at 27, to a rod 28, the pivots 27 being offset from the pivots 21 so that by shifting the rod 28 longitudinally the vanes may simultaneously be rotated between vertical and horizontal positions. The tongues 26 may be bent from top portions of the vanes 18 to provide recesses 29 opening through the tops of the vanes, as shown in Fig. 6, to accommodate the rod 28. The vanes 18 preferably are of such widths, and their pivots 21 preferably are spaced such distances apart, that when said vanes are rotated to horizontal positions, as indicated by dotted lines in Fig. 3, they are disposed in a common plane, substantially in edge to edge abutting relationship, so as to completely or substantially completely close the central rectangular area of the damper against flow of supplied air directly downwardly therethrough to the outlet device B.

Any suitable means may be provided to connect together the two sets of vanes 18 for simultaneous reverse rotation of the vanes of these two sets relative to each other. In this connection and as illustrated by way of example in the drawings, a pair of links 30, 30 may be pivotally connected at their upper ends to a cross head 31 and may extend downwardly and inwardly from said crosshead and at their lower ends may be pivotally connected, one to each set of the vanes 18, through the instrumentality of the pivot element 27 which connects the innermost vane of the related set to the related rod 28. Thus, by vertical movement of the crosshead the links 30, 30 will be caused to act in conjunction with the rods 28 and in an obvious manner to simultaneously rotate the two sets of vanes in opposite directions either toward vertically disposed open positions or horizontally disposed closed positions, depending upon whether the crosshead is moved upwardly or downwardly.

According to the embodiment of the invention illustrated in Fig. 1 of the drawings the crosshead 31 has connected thereto by means of a rod 32 a suitable thermostat device, designated generally as C, which is suitably mounted in the path of flow of the air supplied to the outlet device B whereby said crosshead is raised and lowered in response to changes in temperature of the supplied air to adjust the vanes 18 to regulate flow of the supplied air through the central portion of the damper. No novelty in respect to the thermostat device per se is claimed and therefore a

detailed description of the same is deemed unnecessary.

In Fig. 7 of the drawings is illustrated an alternative means of raising and lowering the cross-head 31. According to Fig. 7 a suitable bearing 33 is suitably mounted below the vanes 18 in vertical alinement with the central portion of the crosshead 31, a vertical shaft 34 is rotatably mounted in said bearing and is held thereby against vertical movement and at its upper end is threaded on the central portion of the cross-head 31, and on said shaft is fixed a sheave 35 around which extends a rope, cord, cable or the like 36 which may lead to any desired point for manual manipulation to rotate said sheave and shaft, thereby to cause said shaft, because of its threaded connection with the crosshead 31, to raise or lower said crosshead and thus rotatably adjust the vanes 18.

Preferably, but not necessarily, all of the vanes 15, 18 and 24 are turned upon themselves at their tops as indicated at 37 to provide rounded edges for the purpose of avoiding or reducing noise incident to the supplied air impinging against and flowing over said edges. Moreover, the corners of the vanes 24 preferably are removed, as indicated at 38, so that the different sets of said vanes are adjustable without interference with each other at their ends.

The vanes 18 are intended primarily to regulate the volume of air flowing to the central portion of the outlet device B. On the other hand, while the sets of vanes 15 and 24 also are effective to regulate the volume of air flowing through the damper, these sets are intended primarily for adjustment to secure either equalized, or substantially equalized, air flow to the different portions of the outlet device B, or a greater or lesser volume of air supply to any given portion of said outlet device as may be desired in any particular instance.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. A damper comprising a central set of parallel spaced apart rotatably adjustable vanes disposed in a common plane, a plurality of other sets of parallel spaced apart rotatably adjustable vanes each disposed outwardly of said central set of vanes and in a plane parallel to and spaced from the plane of said central set of vanes, and other sets of vanes disposed in planes at right angles to the planes of said central set and said other sets and extending between the margins of said central set and the inner ends of said other sets.

2. A damper comprising a central set of horizontal parallel spaced apart rotatably adjustable vanes, a plurality of other sets of horizontal parallel spaced apart, rotatably adjustable vanes disposed outwardly of and above said central set of vanes, and vertical sets of horizontal parallel spaced apart rotatably adjustable vanes at the sides and ends of said central set of vanes and between said central set of vanes and the sets of vanes thereabove.

3. A damper comprising a central set of horizontal parallel spaced apart rotatably adjustable vanes, other sets of horizontal parallel

spaced apart rotatably adjustable vanes above and one at each side and one at each end of said central set of vanes, and vertical sets of horizontal parallel spaced apart rotatably adjustable vanes one at each side and end of said central set of vanes and between said central set of vanes and the related set of vanes thereabove.

4. A damper comprising a horizontal frame substantially in the shape of a Greek cross having four arms each including a pair of side rails, a set of horizontal parallel spaced apart vanes extending transversely across each arm of said frame and pivotally mounted at their ends upon the related side rails of said frame for rotatable adjustment, a vertical member carried by and depending from said frame at each of the four corners where adjacent arms thereof meet, a vertical set of horizontal parallel spaced apart vanes between each adjacent two of said vertical members and pivotally mounted at their ends upon their related vertical members for rotatable adjustment, rails connecting opposite pairs of said vertical members adjacent to their lower ends, and a set of horizontal parallel vanes spaced apart along and pivotally mounted at their ends upon said last mentioned rails for rotatable adjustment.

5. A damper comprising a central set of parallel spaced apart rotatably adjustable vanes disposed in substantially a common plane, a plurality of other sets of parallel spaced apart rotatably adjustable vanes disposed outwardly of and adjacent to said central set of vanes substantially in planes parallel to the plane of said central set, mounting means for said other sets of vanes, and means mounting said central set of vanes for unitary adjustment in directions at right angles to the plane thereof and relative to said other sets of vanes.

6. A damper to be mounted in an air or gas duct to regulate and direct flow of air or gas therethrough, said damper comprising a frame including more than two arms disposed substantially radially with respect to the center of said frame, each arm comprising a pair of parallel spaced apart side rails, and a separate set of air or gas deflecting and volume regulating vanes mounted between the side rails of each of said arms.

7. A damper to be mounted in an air or gas duct to regulate and direct flow of air or gas therethrough, said damper comprising a frame including more than two arms disposed in a common plane and extending substantially radially with respect to the center of said frame, each arm comprising a pair of parallel spaced apart side rails, and a separate set of air or gas deflecting and volume regulating parallel vanes mounted between the side rails of each of said arms.

8. A damper to be mounted in an air or gas duct to regulate and direct flow of air or gas therethrough, said damper comprising a frame including more than two arms disposed radially with respect to the center of said frame, each arm comprising a pair of parallel spaced apart side rails, and a separate set of air or gas deflecting and volume regulating vanes mounted between the side rails of each of said arms in the plane thereof.

9. A damper to be mounted in an air or gas duct to regulate and direct flow of air or gas therethrough, said damper comprising a frame including more than two arms disposed radially with respect to the center of said frame, each

arm including a pair of parallel spaced apart side rails, and a separate set of vanes mounted in each arm between the side rails thereof, the vanes of each set extending transversely of their related arm and being mounted at their ends upon the side rails thereof, said arms and said vanes all being disposed in a common plane.

10. A damper to be mounted in an air or gas duct to regulate and direct flow of air or gas therethrough, said damper comprising a frame including a central portion and more than two arms disposed radially with respect to the center of said central portion, a separate set of air or gas deflecting and volume regulating parallel vanes mounted in each of said arms, and a central set of parallel vanes mounted in a common plane in the central portion of said frame forwardly with respect to said first mentioned sets.

11. A damper to be mounted in an air or gas duct to regulate and direct flow of air or gas therethrough, said damper comprising a frame including more than two arms disposed in a common plane and extending radially with respect to the center of said frame, each arm including a pair of spaced apart parallel side rails, a separate set of air or gas deflecting and volume regulating parallel vanes in and extending transversely of each arm and mounted between the side rails thereof, said sets of vanes being disposed in the plane of said arms and the vanes of each set being mounted at their ends upon the side rails of their related arm.

12. A damper to be mounted in an air or gas duct to regulate and direct flow of air or gas therethrough, said damper comprising a frame including more than two arms disposed in a common plane and extending radially with respect to the center of said frame, each arm including a pair of spaced apart side rails, a separate set of air or gas deflecting and volume regulating parallel vanes mounted in each of said arms in the plane thereof, a central set of air or gas deflecting and volume regulating vanes mounted in said frame inwardly with respect to said first mentioned sets and disposed in a plane parallel to and spaced from the plane of the vanes of said first mentioned sets, and other sets of air or gas deflecting and volume regulating vanes disposed in planes at right angles to said first mentioned sets and said central set and extending between the margins of said central set and the inner ends of said first mentioned sets.

13. A damper as set forth in claim 12 including means mounting the central set of vanes for adjustment toward and away from the plane of the first mentioned sets of vanes.

14. A damper to be mounted in an air or gas duct to regulate and direct flow of air or gas therethrough, said damper comprising a frame including four arms disposed in a common plane and extending radially with respect to the center of said frame, each arm including a pair of spaced apart side rails, a separate set of air or gas deflecting and volume regulating parallel vanes mounted in each of said arms, a member extending at right angles to said frame from each of the four corners thereof where the side rails of adjacent arms meet, a set of air or gas deflecting and volume regulating parallel vanes mounted between each adjacent two of said members, rails connecting opposite pairs of said members, said member-connecting rails being disposed parallel to and being spaced from the plane of said first mentioned sets of vanes, and another set of air or gas deflecting and volume regulating parallel vanes mounted between and supported at their ends by said member-connecting rails.

15. A damper as set forth in claim 14 in which certain of the side rails of the frame arms are joined together at their outer ends by connecting members for use in fastening the damper in a duct.

16. A damper as set forth in claim 10 including means mounting the central set of vanes for unitary adjustments in directions perpendicular to the plane thereof relative to the first mentioned sets of vanes.

17. A damper to be mounted in an air or gas duct to regulate and direct flow of air or gas therethrough, said damper comprising a frame including a plurality of arms each including a pair of parallel spaced apart side rails, said arms being disposed in a common plane, a separate set of parallel vanes in each arm disposed in the plane thereof and extending transversely between and mounted at their ends upon the side rails thereof, and a central set of parallel spaced apart vanes disposed in a common plane parallel to the plane of said arms and said first mentioned sets of vanes and mounted in the central portion of said frame forwardly with respect to the vanes of said first mentioned sets.

18. A damper as set forth in claim 17 including means mounting the central set of vanes for unitary adjustments in directions perpendicular to the plane thereof relative to the sets of vanes that are mounted in the arms.

FRANZ J. KURTH.
